UNITED STATES PATENT OFFICE.

STEWART E. McMILLIN, OF LAWRENCE, KANSAS.

RAILROAD-SPIKE.

1,168,320.

Specification of Letters Patent. Patented Jan. 18, 1916.

Application filed May 9, 1914. Serial No. 837,498.

To all whom it may concern:

Be it known that I, STEWART E. McMILLIN, a citizen of the United States, residing at Lawrence, in the county of Douglas and

5 State of Kansas, have invented certain new and useful Improvements in Railroad-Spikes, of which the following is a specification.

10 My invention relates to railroad spikes and more particularly to that class having a locking device associated therewith.

15 The primary object of my invention is to provide an improved means for mounting a locking device in a railroad spike for securing the spike in a rigid position with respect to the tie and rail.

20 Another object of my invention is to provide an improved locking device having means associated therewith for holding the locking device in an operative position within the spike.

25 A further object of my invention is to provide an improved form of locking device for a tie having means formed on the lower end thereof for facilitating the engagement with the tie.

30 A still further object of my invention is to provide a device of the character described that is simple in construction, efficient in operation and one that can be manufactured and placed on the market at a minimum cost.

35 Other objects as well as the nature, characteristic features and scope of my invention will be more readily understood from the following description taken in connection with the accompanying drawings and pointed out in the claims forming a part of this specification.

40 Referring to the drawings: Figure 1 is a rear elevational view of my invention; Fig. 2 is a side elevational view of my invention, partly in section showing especially the locking device in a position before being applied to a tie; Fig. 3 is a sectional view of the tie and rail showing my invention applied thereto in a locked position; and Fig. 4 is a fragmentary sectional view taken on the line 4—4 of Fig. 3.

45 Referring more particularly to the drawings wherein similar reference numerals designate corresponding parts throughout the different views, I provide the shank 1 of a spike with a head 2, the lower end of the shank being beveled to form a point 3. The 50 rear face 4 of the spike is provided with a longitudinally arranged inwardly extending

recess 5, the lower end of which tapers to a point 5' and is provided with a tapering inner wall 6 which extends upwardly toward the rear face 4.

60 Pivotedly mounted in the alining openings 7 by means of a pin 8 and positioned between the side walls of the recess is a locking element 9. The locking element in this instance conforms substantially to the contour of the recess 5 and consists of a shank 10 which is enlarged intermediate its ends and provided with an opening for engagement with the pin 8 and has its lower end formed into a substantial hook 11, the sides of which are 70 beveled to form a cutting edge 12 which terminates in a point 13 for facilitating the engagement of the locking element with a tie.

75 For the purpose of holding the upper portion of the locking element in a position beyond the plane of the rear face of the tie and for holding the point 13 in alinement with the rear face thereof, I have secured to the inner wall by a suitable fastening device, 80 preferably a screw 14 one end of a substantially S-shaped leaf spring 15 at a point slightly above the pivot point of the locking element, the free end of which bears against the inner face of the upper portion of the 85 shank 10 of the locking element 9.

The operation of my device is as follows: When it is desired to secure the rail 16 in position on the tie 17, the spike 1 is placed within the aperture 18 in the rail and driven 90 downward. The point 13 is arranged in alinement with the rear face of the wall and the upper portion of the shank 10 projects laterally at a substantial acute angle beyond the rear face 4 of the spike. When the 95 upper end of the locking element 9 is engaged by the rail or tie when the same is being driven thereto, the upper portion thereof will be forced inwardly against the tension of the spring 15 and the point 13 of the hook 11 will be forced outwardly into locking engagement with the tie 17, the cutting edge 12 of the locking element greatly facilitating the engagement with the tie and preventing the same from becoming 100 broken.

I desire to be understood that great stress is laid upon the point 13 and the cutting edge 12 of the hook 11. This arrangement 110 greatly facilitates the engagement of the locking element 9 with the tie and because of the same the danger of breakage is

duced to a minimum. Attention is also called to the fact that the shank of the locking element is enlarged about the pivot opening for the purpose of strengthening the same and for preventing the same from becoming broken.

From the above description taken in connection with the accompanying drawings it can easily be seen that I have provided a device that is simple in construction, containing but a few simple parts that can be easily manufactured and assembled and when assembled can be placed on the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent is:—

1. A railroad spike including a head, a pointed shank, a locking element pivotally and resiliently mounted within a corresponding recess in the shank, the upper end of said element normally extending beyond the surface of the shank, the lower end of the element being normally arranged in alignment with the surface of the shank, and the lower edge of the lower end of the element being beveled to form a cutting edge for facilitating the engagement with a tie when the upper end of the element is forced into

the recess during the application of the spike.

2. A rail spike including a head and a pointed shank, said shank provided with a longitudinally arranged tapering recess, a locking element pivotally mounted within and conforming to the contour of the recess, a pointed hook formed on the lower end of said element, the lower edge of the hook being beveled to form a cutting edge, and resilient means positioned within the recess and bearing against the upper end of the locking element for maintaining the pointed hook in alignment with one of the faces of the shank.

3. A rail spike comprising a head and a pointed shank, said shank provided with a longitudinally arranged inwardly extending recess, said recess provided with a tapering wall, a locking element pivotally mounted within and conforming to the contour of said recess, a pointed hook formed on the lower end of said element, the lower edge of said hook being beveled to form a cutting edge, and a leaf spring secured to the tapering wall of the recess, the free end of said spring bearing against the upper portion of said locking element for holding the upper portion thereof in a plane beyond the plane of the face of the shank and maintaining the pointed hook in alignment with the face.

In testimony whereof I affix my signature in presence of two witnesses.

STEWART E. McMILLIN.
